B. GERLA

CONCEALED CLASP

Filed July 6, 1923

FIG. 4

Inventor
Bernard Gerla

By *Bernard Gerla*
Attorney

Patented Apr. 14, 1925.

1,533,702

UNITED STATES PATENT OFFICE.

BERNARD GERLA, OF NEW YORK, N. Y.

CONCEALED CLASP.

Application filed July 6, 1923. Serial No. 649,827.

To all whom it may concern:

Be it known that I, BERNARD GERLA, a citizen of the United States, residing at New York, in the county of New York and State 5 of New York, have invented certain new and useful Improvements in Concealed Clasps, of which the following is a specification.

This invention relates to necktie clips such as are commonly used to secure the ends of 10 a four-in-hand tie to the shirt, to hold the tie ends neatly in position.

The present invention which is a further development of one disclosed in a previous application for patent filed by me on April 15, 1923, under Serial No. 630,245 and has for a general object the provision of a simple and inexpensive form of tie clip which will engage and secure both ends of the tie, and will be invisible when in place.

20 For further comprehension of the invention, and of the objects and advantages thereof, reference will be had to the following description and accompanying drawing, and to the appended claims in which the various novel features of the invention are 25 more particularly set forth.

Fig. 1 of the drawings is a perspective view showing one form of my improved tie clip.

30 Fig. 2 is a side view thereof.

Fig. 3 is a perspective view of a modification.

Figs. 4 and 5 are respectively face and side views of a further modification.

35 Referring now to Figs. 1 and 2 of the drawing my improved tie clip is here formed of a single strip of resilient sheet metal which is folded upon itself to form three reaches which are indicated respectively at 10, 11 and 12, the strip being of greatest 40 width at the point where the two reaches 10 and 11 join together.

These two elements 10 and 11 are inclined toward one another from their joined ends 45 toward their other ends, the last named end of the element being in the form of a backwardly curved lip 13 extending slightly beyond the element 11. The edge of the shirt and the inner tie end are received between 50 these two elements 10 and 11, and to aid in gripping the said parts, projections 14 may be formed on the adjacent faces of these two elements.

The third reach or element 12, is tapered 55 to a point to form a pin and is formed with a number of transverse corrugations 16

spaced therealong. This reach is of slightly less length than the intermediate reach 11 to which it is joined, and the latter has struck therefrom, adjacent the end thereof which 60 joins with the element 10, a rearwardly facing tongue 17 which forms a safety lock to receive the pointed end of the element, the rear end of this tongue, being transversely curved as at 18 to form a V-shaped recess 65 on the inner side thereof receiving said pointed end and holding it against lateral displacement.

In the use of my improved tie clip as just described the shirt and inner tie end are 70 gripped between the elements 10 and 11 as above stated and then the pointed element 12 is passed through the back element of the outer tie end and sprung under the tongue 17. The two tie ends are thus held in place, 75 as will be apparent, while the clip is concealed by the outer tie end.

The clip shown in Fig. 3 differs from that shown in Figs. 1 and 2 only in the slightly different form of the tongue 17 for engaging 80 the element, the root of this tongue being turned toward the element 12, while the tongue is curved backwardly with its extreme end downturned toward the element 11, and notched as at 18'.

The form shown in Figs. 4 and 5 is in the main similar to that shown in Figs. 1 and 2, differing only in that a second tongue 30, is struck from the intermediate element 11 and is curved in bow form into the space between 90 the elements 10 and 11 and is adapted to have its free end press outwardly on the pin element 12 to lock the same in place engaging the tongue 17, when the shirt and outer tie end are inserted between the parts 10 95 and 11.

The form shown in Fig. 7 differs from that shown in Fig. 6 only in having the pin 20' corrugated and in omitting the lugs 25.

While I have shown and described a preferred embodiment and use of my improved concealed clasp it is to be understood that I do not limit myself to the precise construction herein disclosed nor to the use of the same only for necktie clasp but also for invisible lingerie strap clasp, hair clasp, or for other uses, and the right is reserved to all changes and modifications coming within the scope of the invention as defined in the appended claims.

Having thus described my invention what I claim as new and desire to protect by Let-

ters Patent of the United States is as follows:

1. A tie clip comprising a flat strip of metal doubled upon itself to form an intermediate reach and two outer reaches, one of the outer reaches being pointed to form a pin, the other outer reach projecting at its free end beyond the adjacent end of the intermediate reach, said free end being in the form of an outwardly curved lip.
2. A tie clip comprising a flat strip of metal doubled upon itself to form an intermediate reach and two outer reaches, one of the outer reaches being pointed to form a pin, the other outer reach projecting at its free end beyond the adjacent end of the intermediate reach, said free end being in the form of an outwardly curved lip, and a safety catch in the form of a tongue struck out from said intermediate reach for engaging the free end of said pointed reach.
3. A tie clip comprising a flat strip of metal doubled upon itself to form an intermediate and two outer reaches, one of the outer reaches being pointed to form a pin, a safety catch on said intermediate reach for

engaging the free end of said pointed reach, and a tongue struck out from said intermediate reach and adapted to bear on said pointed reach at a distance from the free end of the latter to retain the said free end engaged with said safety catch.

4. A tie clip comprising a flat strip of metal doubled upon itself to form three reaches presenting separate pockets, one of said reaches being pointed to form a pin, and a safety catch for engaging the said pointed reach, said pointed reach being formed with transverse corrugations.

5. A tie clip comprising a flat strip of metal doubled upon itself to form three reaches presenting separate pockets, one of said reaches being pointed to form a pin, and a safety catch for engaging the said pointed reach, said pointed reach being formed with transverse corrugations, and said safety catch being in the form of a tongue struck out from said strip and having a V-end.

In testimony whereof I have affixed my signature.

BERNARD GERLA.
